No. 37,297.

Patented January 24, 1905.

UNITED STATES PATENT OFFICE.

HARRY S. MADDOCK, OF TRENTON, NEW JERSEY.

DESIGN FOR A MUG OR STEIN.

SPECIFICATION forming part of Design No. 37,297, dated January 24, 1905.

Application filed December 14, 1904. Serial No. 236,876. Term of patent 7 years.

To all whom it may concern:

Be it known that I, HARRY S. MADDOCK, a citizen of the United States, and a resident of Trenton, in the county of Mercer and State of New Jersey, have invented a new, original, and ornamental Design for Mugs or Steins; and I do hereby declare that the same is fully and clearly illustrated in the accompanying drawing, forming part of this specification.

The drawing illustrates a side view of a mug or stein embodying the design.

What I claim as my invention is—

The ornamental design for a mug or stein herein shown.

HARRY S. MADDOCK.
